UNITED STATES PATENT OFFICE.

ZERAH R. NILES, OF ONEIDA, NEW YORK.

PENDULUM-ADJUSTMENT FOR CLOCKS.

SPECIFICATION forming part of Letters Patent No. 268,524, dated December 5, 1882.

Application filed September 22, 1882. (No model.)

To all whom it may concern:

Be it known that I, ZERAH R. NILES, of Oneida, in the county of Madison, in the State of New York, have invented new and useful 5 Improvements in Pendulum-Clocks, of which the following, taken in connection with the accompanying drawings, is a full, clear, and exact description.

This invention relates to improved means 10 for preventing too deep entrance of the pallets of the verge between the teeth of the escapement-wheel and the resultant stoppage of the clock incident to displacement of the clock from a true perpendicular position; and it 15 consists essentially in the combination of a clasp embracing the pendulum-rod between laterally-elongated friction-bearings, a guide-wire extended from the verge and connected with the clasp, and banking-pins arranged to 20 limit the motion of the guide-wire, all as hereinafter more fully described, and specifically set forth in the claims.

Referring to the annexed drawings, Figures 1 and 2 are front views of a clock provided 25 with my improvements, showing it in different positions; and Fig. 3 is an enlarged side view of the clasp, which is connected with the pendulum-rod.

Similar letters of reference indicate corresponding parts.

A denotes the escapement-wheel, B the verge, and P the pendulum-rod, all arranged and connected to the frame F in the usual manner.

35 This class of clocks, when in proper order, require a perfect perpendicular position in order to produce a perfect escapement of the pallets *a a* of the verge on the escapement-wheel B, owing to the natural equalized vibration of 40 the pendulum in opposite direction from a perpendicular line, and the tilting of the clock from a perfect perpendicular position causes the pendulum to throw one of the pallets too deep into the interstices between the teeth of the 45 escapement-wheel, and thereby stops the running of the clock. This effect I prevent by the following instrumentalities: To the pendulum-rod I connect a self-adjusting clasp in the form of a plate, C, having a horizontally-elongated 50 base, *b*, and a spring-bail, *c*, attached to the two edges of said base and extended upward there-

from. The pendulum-rod P, passing between the plate C and bail *c*, causes said plate to become clasped thereon by the pressure of the bail *c* on the pendulum-rod. The upper end 55 of the plate C is provided with a projection or offset, *u*, which is slotted to engage the usual thin flexible upper portion of the pendulum-rod. On the edge of the plate C is attached vertically a wire, forming a vertically-elongated 60 loop or slot, *d*, through which projects the end of the guide-wire *e*, the opposite end of which is firmly connected to the verge B.

r r are two stop-pins or banking-pins, fixed 65 to the frame F at opposite sides of the guide-wire *e*, and at such a distance asunder as to confine the vibration of said guide-wire within proper limits to maintain a perfect escapement of the pallets of the verge on the escapement-wheel.

The operation of the described devices is as follows: When the clock stands in a perfect perpendicular position, as illustrated in Fig. 1 of the drawings, the clasp C normally assumes a central position on the pendulum-rod, 75 there being no strain to displace it; but in case the clock is placed in an inclined position, as shown in Fig. 2 of the drawings, then the gravity of the pendulum causes the guide-wire *e*, by its collision with the banking-pins 80 *r r* and its connection with the elongated loop *d* of the clasp, to draw the base of the clasp C to one side on the pendulum-rod, the connection of the slotted projection *u* with the flexible upper portion of the pendulum-rod 85 serving as a fulcrum in the aforesaid movement of the clasp. The spring-bail *c* produces a sufficient frictional hold of the clasp on the pendulum-rod to cause the latter to carry with it in its vibrations the said clasp in 90 its shifted position, and thus maintain the clock in operation.

It will be observed that the spring-bail *c* adapts the clasp to be attached to pendulum-rods of different sizes, and maintains uniform 95 the frictional hold of the clasp on the pendulum-rod. The width of the base *b* of the clasp can be gaged according to the height of the clock and sweep of the pendulum.

Having described my invention, what I claim 100 as new, and desire to secure by Letters Patent, is—

1. In a pendulum-clock, the combination of a clasp embracing the pendulum-rod between laterally-elongated frictional bearings, a guide-wire extended from the verge and connected with the clasp, and banking-pins arranged to limit the motion of the guide-wire, substantially as set forth.

2. The combination, with a pendulum and verge, of the clasp consisting of the plate C, having the slotted projection *u*, broad base *b*, spring-bail *c*, and guide *d*, the guide-wire *e*,

engaging the guide *d*, and the banking-pins *r r*, all as described and shown.

In testimony whereof I have hereunto signed my name and affixed my seal, in the presence of two attesting witnesses, at Syracuse, in the county of Onondaga, in the State of New York, this 12th day of September, 1882.

ZERAH R. NILES. [L. S.]
